UNITED STATES PATENT OFFICE.

ARTUR HERMANN, OF LEIPZIG-GOHLIS, GERMANY.

ELECTROLYTIC APPARATUS.

1,115,671.

Specification of Letters Patent.

Patented Nov. 3, 1914.

Application filed April 23, 1914. Serial No. 833,974.

To all whom it may concern:

Be it known that I, ARTUR HERMANN, a citizen of the German Empire, residing at Leipzig-Gohlis, Germany, have invented 5 certain new and useful Improvements in Electrolytic Apparatus, of which the following is a specification.

This invention relates to electrolytic apparatus, and it comprises an electrolytic apparatus 10 comprising a rotating wheel or trolley electrode having a grooved periphery with a centered comparatively narrow ring of conducting material with non-conducting material on each side; such electrode advantageously 15 consisting of a central grooved wheel of metal and an inclosing wheel of insulating material composed of two guide disks making a tight joint with the rim edges of said metal wheel and extending radially 20 therebeyond; all as more fully hereinafter set forth and as claimed.

In electrolytic processes of treating metal wares, such as wire and sheets, as moving bodies, continuously or in long lengths, 25 whether the material be an anode, as in electrolytic cleansing and pickling methods, or a cathode, as in galvanizing and plating, it is ordinarily desirable to have electric connections therewith at intermediate points 30 along its length; at points where it is immersed in the electrolyte. Such connections may be made by various forms of rolling or sliding contacts but in practice the devices heretofore used have all been open to the 35 serious objection that the wetted and electrically active surface was much more than was necessary to make the connection. In pickling processes this leads to corrosion or undue wear of the electrode; and in plating processes it leads to a deposition of metal on the contact device and to a wasteful consumption of current. Many efforts 40 have been made to obviate this with the use of stationary insulating diaphragms or 45 shields or of insulating varnishes, but neither has proved practical. The diaphragms or shields take up too much room and render the operation complicated; and are besides, and especially when near the 50 wire, apt to be broken or injured. Varnishes and paints are always porous; and may allow development of growths of crystalline metal with short circuits, arcing, interference with movement, etc. Diaphragms 55 or shields in practice must usually be mounted with metal screws, rivets, etc., which

must be varnished or painted. And with the usual devices the current conducting surface is usually greater than is required for that purpose since otherwise the wire 60 would work off.

In the present invention the electrode is adapted to make rolling contact but the peripheral conductive surface is but little broader than the wire. On each side of the conductor proper is fastened an easily removable insulating guide disk of greater diameter. The inner faces of these disks are slightly sloped to give an outwardly widening space therebetween, radially beyond the peripheral face of the conductor wheel proper. These side disks are notched somewhat to accommodate the rim of such wheel and make a fluid tight joint therewith. The space is just wide enough to 75 accommodate the wire. At the periphery, the space widens somewhat to form a groove capable of taking irregularities, joints, etc., of the wire.

With this arrangement the wire runs 80 smoothly, and much current cannot flow between the conductor and the solution.

In the accompanying illustration I have shown, more or less diagrammatically, certain embodiments of the present invention. 85 In this showing,

Figure 1 is a side view of an electrode according to the present invention; Fig. 2, is a vertical transverse section along line 2—2 of Fig. 1; Figs. 3 and 4 are corresponding showings of a somewhat modified form; Fig. 5 is a plan view of the galvanizing or pickling bath provided with electrodes according to the present invention; Fig. 6 is a longitudinal central vertical section along line 6—6 of Fig. 5; and Fig. 7 is a view of a connection between lengths of wire.

In the showing of Figs. 1 and 2, the electrode proper is a wheel 1 of acid proof bronze or other suitable material. It may be made up of spokes 2 and rim 3. This rim is grooved and but little wider than the wire or other article to be treated. Upon the hub 4 are mounted wire guiding and holding means such as two guide disks or wheels 5 and 6. As shown, these disks are recessed at 7 to accommodate the rim of the wheel with which they overlap and with which they make a substantially water tight joint; the wheel and the disks thus have complementary parts so that the disks cover all of the 100 105 110

wheel except the groove for a wire. As shown, these disks extend outwardly some little distance beyond the rim of the conductor wheel and are spaced apart so as to form channel 8, this channel widening slightly outward. The peripheral surface of the two disks is cut away to form flat groove 9. The space between the disks is so narrow that the metal ware under treatment just goes 10 through it freely.

In order to allow joints and the like to run over the electrode without interruption, the relation of the diameter of the conductor wheel proper to that of the side disks is 15 such that the circumference of the side disks cuts the direction of the wire at such an angle that even in the event of occurrence of crooks and points, as, for instance, at joints, rotation of the device still continues 20 without great consumption of power, the joints, etc., being lifted out of the guide space.

Wheel 1 may have a hub 10 mounted in a yoke shown in two parts, 11 and 11^a, connected at 12 and making connection with conductor 13 which may be of copper and shown as mounted on angle iron 14. 11^a is rigid and 11 movable. This structure provides a ready means of disassembling the 25 structure. The guide disks may be provided with hooks or lugs 15 engaging the spokes on the wheel proper. Assuming that in normal position, the wheel is running clockwise, on separating the yoke and turning the 30 disks counter-clockwise the hooks no longer engage the spokes and the wheel structure readily comes apart. With this structure no metal parts of the wheel other than the wire-carrying periphery come into contact 35 with the solution and dismounting requires no tools. Bronze rings 16 may be provided 40 on the hub to insure centering of the guide rolls. As shown in Fig. 4 these rings 16^a may be broad enough to cover the inner or 45 perforated side of the guide disks and hold them on the hub of the conductor wheel without further fastening. In the structure of Figs. 3 and 4, an additional joint 17 is used which allows the yoke to move upward 50 in case of an unusually difficult joint going past the conductor. In normal operation its weight holds it in the position shown. In the illustration the yoke is shown secured in place by screw 18. This is useful when 55 it is desired to move the conductor from the bath.

In Figs. 5 and 6, 19 is the usual bath tub or tank for holding the electrolyte. It is shown provided with current conductors 20 carrying the usual conducting rolls 21. Non-conductive rolls 22 guide wire 23. In this structure, which is shown as a galvanizing bath, 24—24 are anodes secured in electrodes 25 connected to cross conductors 26. 60 Non-conductive guide rolls 27 are provided

in the vicinity of the conductive devices of the present invention.

The described apparatus is particularly suitable for plating and galvanizing purposes. In its use, the formation of a precipitate in the electrolytic bath or deposition of any material amounts of metal on the conductor is almost completely prevented, even under the most unfavorable conditions, as when no wire passes through the bath. 75 Further, it accomplishes an economy in operation since the usual frequent changing and cleaning of the rolls are avoided as well as interruption in operation. Injury to the coating upon the wire by sparking is almost completely avoided inasmuch as interruption of the current and sparking only occur when the joints pass the conductor, and this passage is at a point where arcing and sparking cannot readily occur. Damage to the guide 80 rolls 5 and 6 is practically excluded by their form.

A further great advantage of this structure resides in the fact that it allows with the usual voltage in the bath a considerably 90 higher current density so that with a similar amount of deposition in a given time a materially higher speed of passage of the wire is possible. Or conversely, with a given amount of metal deposition the necessary 95 length of the apparatus may be materially shortened.

In Fig. 7 are shown two wires as connected with the usual loops 28 and 29; this showing being merely to illustrate with what the 100 apparatus must cope.

What I claim is:

1. In an electrolytic apparatus, a contact wheel having a narrow conductive grooved periphery with lateral continuations of non-conductive material. 105
2. In an electrolytic apparatus, a contact wheel having laterally secured disks of insulating materials of greater diameter than said wheel. 110
3. In an electrolytic apparatus, a contact wheel having laterally secured disks of insulating materials of greater diameter than said wheel, the space between said disks beyond said periphery narrowing radially inward. 115
4. In an electrolytic apparatus, a contact wheel having a narrow conductive rim and having sides of non-conductive material, said sides extending over the edge of said rim. 120
5. In an electrolytic apparatus, a contact wheel having spokes and a narrow conductive rim, side-disks of non-conductive material and hook-connections for said disks 125 engaging said spokes.
6. In an electrolytic apparatus, a contact device comprising a pivoted yoke, a narrow-rimmed conductor wheel held in said yoke, a disk of non-conducting material engaging 130

- each side of said wheel and means for removably securing said disks to said wheel.
7. In an electrolytic apparatus, a contact device comprising a narrow rimmed conductor wheel and side disks of non-conductive material on each side of said wheel, said disks forming a rim continuing the rim of said wheel and means for removably securing said disks to said wheel.
- 10 8. In an electrolytic apparatus, a contact device comprising a narrow rimmed conductor wheel and side disks of non-conductive material on each side of said wheel, said disks extending radially beyond said wheel 15 with a wire receiving space therebetween and having a shallow continuing groove on their outer face.
9. In an electrolytic apparatus, a contact device comprising a narrow rimmed conductor wheel, a pair of side disks of insulating material covering the sides of said wheel, means for removably securing the disks to the wheel, a yoke forming a bearing for said
- 20 wheel and having one arm swingably mounted with regard to the other arm to permit removal of the wheel and means for attaching said yoke to a conductor bar.
10. In an electrolytic apparatus a contact wheel, and wire guiding and holding means of insulating material for the wheel extending radially beyond and in part overlapping the periphery thereof.
11. In an electrolytic apparatus a contact wheel and separable insulating wire guiding and holding means therefor, the said wheel 35 and holding means having complementary parts whereby the wire holding means may completely inclose the wheel sides.

In testimony, that I claim the foregoing as my invention, I have signed my name in presence of two subscribing witnesses.

ARTUR HERRMANN.
